UNITED STATES PATENT OFFICE

EDWARD B. SPOONAMORE, SR., OF JONESBORO, ARKANSAS

CONCRETE BURIAL VAULT

Application filed January 20, 1931. Serial No. 510,024.

This invention relates to improvements in the method of manufacture and construction of improved concrete burial vaults of the type more frequently referred to in the trade as a mausoleum.

My principal aim is to generally improve upon prior art devices of this general classification by providing a distinguishable contribution to the art which is quite as simple and inexpensive in construction as similar structures with which I am familiar, and which, it is believed, is characterized by features and advantages not found in analogous vaults.

Structurally speaking, one of the principal features of the improved organization of parts is the two-way adhesive seal between the cover and body of the structure, whereby to provide a dependable joint of air and liquid-tight formation.

Another feature of construction is predicated upon the ornamental configuration of the protruding or elevated portion of the cover and an associated marker permitting the complete vault to be buried in the ground at a depth to permit said ornamental top to function as a memorial monument.

A still further feature of the invention is founded upon the special texture of the lid and body portion providing a box-like enclosure which is impervious to the passage of moisture, whereby to provide for desired longevity.

Then too, the improved structure is individualized by the incorporation therein of a horizontal divider or partition concrete slab or plate dividing the interior of the enclosure into upper and lower compartments, a portion of said divider serving to define one wall of a sealing channel, and said divider being constructed of absorbent material to absorb moisture from the lower compartment; said divider also serving so that the top chamber will provide for temperature equalization and appropriate insulation to increase the effectiveness of the complete structure.

Other features and advantages will become more readily apparent from the following description and drawings.

In the drawings:

Figure 1 is a top plan view of a mausoleum or burial vault constructed in accordance with the present inventive conception.

Figure 2 is a side elevational view thereof showing the manner in which it is buried in the ground to serve as a grave marker or monument.

Figure 3 is a central longitudinal sectional view through the complete assembly, with the parts in operative relationship, the section being on the line 3—3 of Figure 1.

Figure 4 is a central transverse section on the line 4—4 of Figure 1.

Figure 5 is a fragmentary sectional view of a portion of the cover.

Figure 6 is a fragmentary sectional view of one corner portion of the body or box.

Figure 7 is a perspective view of the divider.

Figure 8 is a longitudinal section on the line 8—8 of Figure 7.

As shown in Figure 3 for example, the body or receptacle portion of the structure is generally denoted by the numeral 9. This is of customary rectangular configuration and is provided on its interior with an endless rib 10 constituting a supporting ledge.

Formed on the exterior of the rim portion of the box is an outstanding flange 11 whose upper edge is disposed on a plane above the corresponding edge of the rib 10, said upper edge constituting a cover seat. The cover is generally designated by the numeral 12. It comprises a flat topped marginal portion 13 and a concavo-convex or curvate crown portion 14. This is designed for ornamentation purposes.

At one end of the part 14 is a recessed boss 15 to receive a name plate 16, these features serving as a monument, since this part of the structure is exposed above the ground 17 as illustrated in Figure 2 when the vault is embedded. Referring to Figure 5 it will be seen that the marginal portion of the cover is formed on its underside with a depending wall 18 adapted to be seated on and sealed to the flange 11. Spaced inwardly from and formed on the inner side of the wall is a relatively short substantially wedge-shaped end-

less tongue 19 which may be designated as a key.

The numeral 20 designates as a unit, the removable partitioning divider which as before indicated comprises a substantially rectangular plate or concrete slab 21 whose marginal portion is adapted to rest on the ledge 10. Formed integrally on and rising from the top of the plate is a surrounding upstanding rectangular frame 22. This is spaced inwardly from the marginal edges of the plate and has a double function. It is adapted for close spaced relationship with respect to the underside of the cover and further functions as a wall to co-operate with the adjacent part of the rim of the box in defining a channel, said channel serving as a keyway for reception of the aforesaid key 19.

The sealing compound, which is of a suitable adhesive type, is generally designated by the ordinals 23 and it is filled into the spaces between the depending projecting portions on the under marginal portion of the cover and the associated details of the divider and upper portion of the body. Otherwise stated, the major portion of the sealing compound is located in the channel defined between the frame 22 and the adjacent marginal portion of the rim of the box, thus providing anchorage for the key 19. A portion of the compound also locates itself between the upper edge of the frame 22 and the adjacent under portion of the cover. Moreover, the seal is located between the upper seating surface of the aforesaid flange 11 and the co-operating marginal wall of the cover.

The material to be used in making the triple seal surface mausoleum is as follows: The body 9 is to be made of two parts crushed flint, not over a quarter of an inch in size; one part washed sand; and one part fresh Portland cement. All are to be thoroughly mixed and medium wet so that the complete mass will pour. The crushed flint used is non-absorbent. Metal covered forms with all joints soldered will be used so that no water can be absorbed from the concrete.

The entire mausoleum is to be reinforced with three-eighths and quarter inch steel not farther apart than seven inches each way, bottom, top, sides and ends. After the bottom piece shown has been poured, the forms are to be vibrated both inside and outside to exclude the air in the concrete and make it more compact. This part is to remain in the forms twenty hours. The forms are then removed and a thin coat of cement, which is to be pure cement and water is to be applied to the inside and outside, which is to fill the small air bubbles that were brought to the surface in vibrating.

This piece is then filled full of water and left standing for twenty-one days. This water should stay at a temperature of not

less than sixty-five degrees F. The water is then removed and a coat of water-proofing compound is applied both inside and outside.

The horizontal divider 20 is to be made the same as above with the exception that the crushed rock used is to be an absorbent stone and the mixture is to medium dry mix and it is not to be cured or coated, as this piece is to be of an absorbent nature, so that it will take up any moisture that might rise from the lower chamber, and very important, the inner plate makes possible an inside seal.

The lid or cover 12 is to be of the same material as the body, but is to be a medium dry mix. The entire outside of this cover is to be coated, while wet with a mixture five-eighths of an inch thick of two parts fine crushed granite and one part fresh white cement. It is then to be cured in water, after which it is to be ground smooth on the outside with carborundum brick, then polished to a gloss. There is an impression 15 made in the head piece of the lid for the nameplate or marble, granite or bronze.

The mausoleum is to be made so that it will be at least three inches thick at any point of the walls, bottom or top. It is made in two chambers so that the top chamber will serve as a temperature equalizer and insulation means in extreme hot or cold weather. It also serves as a drying chamber for the lower chamber.

The lid is so constructed that the mausoleum is sealed inside (which is made possible by the inner divider plate). The outside seal is made possible by the dropped wall of the lid. An outstanding feature too, is the marginal wall 18 of the lid extending below the top of the vault when sealed, making it air and moisture tight. The air pressure inside the lid will keep the water out even if it should not be sealed otherwise, making it possible to set them for future use and not seal them. The lid also serves as a monument, one that will not lean or get out of place.

The mausoleum is to be made in different sizes to accommodate different size caskets. In two style lids to conform to different cemetery regulations. The sealing mixture is to be sand and cement in equal proportions.

The foregoing structural features and advantages co-act in a collective and co-herent manner to provide a simple, yet economical vault which will fulfill the requirements of a structure of this class in a dependable and satisfactory manner.

It is thought that the description taken in connection with the drawings will enable a clear understanding of the invention to be had. Therefore, a more lengthy description is thought unnecessary.

While the preferred embodiment of the invention has been shown and described, it is to be understood that minor changes in shape

size, and arrangements of parts coming within the field of invention claimed may be resorted to if desired.

I claim:

- 5 1. In a concrete mausoleum of the class described, a substantially rectangular box-like body portion constituting a receptacle, the upstanding rim thereof being provided on its interior with an inwardly projecting rib
  - 10 10 constituting a supporting ledge and provided on its exterior with an outstanding lid supporting flange, a divider plate of porous material removably seated on said ledge and dividing the body portion into upper and
  - 15 15 lower chambers and said divider plate having an upstanding flange formed therewith, said flange co-operating with an adjacent portion of the rim to define a sealing compound channel, and a cover having a marginal depending
  - 20 20 wall engageable with said first mentioned flange and formed inwardly from said marginal wall with a relatively short endless rib constituting a key for reception in said channel, and sealing compound interposed
  - 25 25 between the contacting portions of the body, cover, and divider.
2. In a concrete burial vault of the class described, a substantially rectangular box-like body including a bottom and an upstanding surrounding rim, said rim being formed on its interior at a point spaced downwardly from the top edge with an inwardly projecting rib constituting a supporting ledge, the rim being formed on its exterior with
  - 30 30 a cover supporting flange spaced downwardly from the top edge of the rim, a horizontal bodily removable divider unit comprising a plate of absorbent material having its marginal portion seated removably on said ledge,
  - 35 35 said plate being formed with an upstanding marginal flange, the outer wall of which slopes upwardly and inwardly, said marginal flange being spaced inwardly from the marginal edges of the plate, said flange co-oper-
  - 40 40 ating with the adjacent surrounding portion of the rim to define a channel adapted for reception of a sealing compound, and a removable cover having a depending marginal wall fitting telescopically down over the ex-
  - 45 45 terior of the upper portion of the rim and resting on said first mentioned flange, and formed on its bottom inwardly from said wall with an endless substantially wedge-shaped rib constituting a key, said key de-
  - 50 50 pending into said channel.

In testimony whereof I affix my signature.
EDWARD B. SPOONAMORE, Sr.
